Primary Examiner — Mary Ann Calabrese*Assistant Examiner* — Jennifer L Rempfer(74) *Attorney, Agent, or Firm* — Tillman Wright, PLLC; James D. Wright; David R. Higgins(57) **CLAIM**

The ornamental design for a bed sheet retainer, as shown.

DESCRIPTION

FIG. 1 is a top orthogonal view of the design for a bed sheet retainer;

FIG. 2 is a bottom orthogonal view of the design for a bed sheet retainer of FIG. 1;

FIG. 3 is a left side view of the design for a bed sheet retainer of FIG. 1;

FIG. 4 is a right side view of the design for a bed sheet retainer of FIG. 1;

FIG. 5 is a top view of the design for a bed sheet retainer of FIG. 1;

FIG. 6 is a bottom view of the design for a bed sheet retainer of FIG. 1;

FIG. 7 is a front view of the design for a bed sheet retainer of FIG. 1; and,

FIG. 8 is a rear view of the design for a bed sheet retainer of FIG. 1.
